(57) **CLAIM**

The ornamental design for a light therapy pad, as shown and described.

DESCRIPTION

FIG. 1 illustrates a front perspective view of a light therapy pad;

FIG. 2 illustrates a front view of the light therapy pad thereof;

FIG. 3 illustrates a back view of the light therapy pad thereof;

FIG. 4 illustrates a left side view of the light therapy pad thereof;

FIG. 5 illustrates a right side view of the light therapy pad thereof;

FIG. 6 illustrates a top view of the light therapy pad thereof;

FIG. 7 illustrates a bottom view of the light therapy pad thereof;

FIG. 8 illustrates a back perspective view of the light therapy pad thereof.

FIG. 9 illustrates an enlarged view of light therapy pad of portion 9 of FIG. 4 thereof;

FIG. 10 illustrates an enlarged view of light therapy pad of portion 10 of FIG. 6 thereof; and,

FIG. 11 illustrates an enlarged view of light therapy pad of portion 11 of FIG. 7 thereof.

The long-short dash lines illustrate the boundary of the magnified portion and form no part of the claimed design. The broken lines shown in the drawings are for purpose of illustrating portions of the light therapy pad, which form no part of the claimed design.
